UNITED STATES PATENT OFFICE.

CHARLES J. PAULSON, OF NEW YORK, N. Y., ASSIGNOR, BY MESNE ASSIGNMENTS, TO
STERLING TYPEWRITER COMPANY, A CORPORATION OF NEW JERSEY.

RIBBON ATTACHMENT FOR TYPE-WRITERS.

1,050,997.

Specification of Letters Patent. Patented Jan. 21, 1913.

Application filed March 20, 1911. Serial No. 615,791.

To all whom it may concern:

Be it known that I, CHARLES J. PAULSON, a subject of the King of Sweden, and resident of the borough of Brooklyn, in the county of Kings, city and State of New York, have invented certain new and useful Improvements in Ribbon Attachments for Type-Writers, of which the following is a specification.

10 This invention relates to bi-chrome ribbon carriers for typewriting machines, and embodies means whereby with the actuation of the finger keys the ribbon carrier alternately rises into and leaves the printing zone, together with means regulating the height to which the carrier rises, in order to bring either portion of a two color ribbon into the printing zone.

15 The purpose of my improvement is to enable the writing to be visible, by removing the ribbon from the printing position after each character impression is made, and to vary the degree of movement of the ribbon carrier according to the color of ink 20 desired to be impressed.

25 In the drawing accompanying this application: Figure 1: is a side elevation of my improved ribbon carrier and actuating means. Fig. 2: is a top plan view thereof. 30 Fig. 3: is a perspective detail of said carrier, and Fig. 4: is a similar view of one of the slideways.

35 In said figures *a* indicates a ribbon guide, which is mounted in slideways *b*, and connected to a yoke *c* that is pivoted at *d* to a support upon the machine frame (not shown). Yoke *c* has a tail piece *e*, which is engaged by an adjustable link *f*, said link being pivoted on a rod *g*, which is supported 40 between the arms *h* said arms *h* being pivoted to the machine frame at *i*. As indicated, the finger keys *j* lie transversely across the rod *g* and depress the latter as they are themselves depressed. The link *f* 45 is drawn downwardly with the depression of rod *g* also the tail piece *e*, thus raising the ribbon guide *a*. The return of the finger key completes the rocking action of the tail piece; yoke and ribbon guide. This return 50 movement is accomplished automatically in any suitable manner upon the release of pressure on the keys as by means of a spring

(not shown) bearing against the arms *h*. The position of link *f* upon tail piece *e* determines the degree of movement to be imparted to the ribbon guide. Thus, with the link *f* at the free end of tail piece *e*, as shown in full lines in Fig. 1, the minimum degree of rocking movement is given the ribbon guide. The bi-chrome ribbon carried in the guide may have its upper portion black and its lower portion red, as indicated, and the rocking movement just described may serve to carry the upper or black portion into the printing zone. But, when the link *f* is in the position indicated in dotted lines, the corresponding stroke of the finger key, acting through link *f* at a point so much nearer the fulcrum, raises the ribbon guide to a greater height and brings the lower or red portion of the ribbon into the printing zone.

Obviously, the device is perfectly automatic, the ribbon entering and leaving the printing zone in a rocking action set up in the manipulation of the finger keys. The determination of the color ink to be employed is effected by moving the link *f* to one or the other of its two positions.

I claim:

In a typewriter, a ribbon carrier, vertical guides therefor, a yoke having both arms thereof pivoted intermediate their ends in a horizontal position to rock vertically, the ends of the yoke arms engaging respectively with opposite sides of the ribbon carrier, and a curved bar extending centrally and rearwardly from said yoke; together with a key lever, a transverse shaft adapted to be depressed by said key lever, a vertical link pivoted on said shaft, said vertical link having an aperture to receive said curved bar, and a handle whereby said link may be shifted from one end of said bar to the opposite end thereof, to thereby vary the degree of vertical throw accorded the ribbon carrier.

Signed at the borough of Manhattan, in the city, county and State of New York this 17th day of January A. D. 1911.

CHARLES J. PAULSON.
